UNITED STATES PATENT OFFICE.

GEORGE E. PHELAN, OF NEW YORK, N. Y.

BILLIARD-TABLE CUSHION.

SPECIFICATION forming part of Letters Patent No. 359,031, dated March 8, 1887.

Application filed June 22, 1886. Serial No. 205,907. (No model.)

To all whom it may concern:

Be it known that I, GEORGE E. PHELAN, of the city, county, and State of New York, have invented a new and useful Improvement 5 in Billiard-Table Cushions, of which the following is a full, clear, and exact description.

Reference is to be had to the accompanying drawing, forming a part of this specification, and which is a sectional elevation of a part of 10 a billiard-table to which my improvement has been applied.

The object of this invention is to provide billiard-table cushions constructed in such a manner that the said cushions will prevent the 15 balls from embedding themselves in the cushions, and at the same time will have an increased elasticity over cushions constructed in the ordinary manner, and will cause the balls to rebound in such directions that the 20 angles of reflection shall be equal to the angles of incidence.

The invention consists in an india-rubber cushion for a billiard-table, having a tube placed in a longitudinal perforation thereof 25 near the operative edge, as will be hereinafter fully described, and then claimed.

A represents the table-bed, B the table side or rail, and C the cushion-bed, all of which parts are constructed and connected in the 30 ordinary manner.

D is the cushion, which is made of india-rubber, in triangular form, and with a longitudinal recess, E, in its base.

In the forward part of the cushion D, near 35 its operative edge, is formed a longitudinal

perforation, F, in which is placed a tube, G, made of hard rubber, gutta-percha, celluloid, metal, or other suitable material.

The table-bed A, the cushion-bed C, and the cushion D are covered with cloth H, in the 40 ordinary manner.

With this construction, when a billiard-ball strikes the cushion D, the tube G prevents the said ball from bedding itself in the said cushion, and at the same time distributes the force 45 of the ball's impact along the cushion for a considerable distance and is itself slightly bent by the blow, so that the ball will be thrown back so strongly by the elasticity of the rubber, supplemented by the elasticity of the tube, 50 that the angle of reflection will be exactly equal to the angle of incidence, and the direction of the rebound can be accurately estimated.

I am aware that india-rubber cushions for 55 billiard-tables have been made with wires embedded along their operative edges; also, with flat plates and metal coils molded into their faces near their operative edges, and I make no claim to such constructions; but 60

What I do claim as of my invention is—

An india-rubber cushion for a billiard-table, having a tube placed in a longitudinal perforation thereof near the operative edge, substantially as herein shown and described.

GEORGE E. PHELAN.
